UNITED STATES PATENT OFFICE.

EDWARD L. STORY, OF EVERETT, MASSACHUSETTS.

BOILER-COVERING.

No. 866,235.

Specification of Letters Patent. Patented Sept. 17, 1907.

Application filed March 23, 1907. Serial No. 384,058.

To all whom it may concern:

Be it known that I, EDWARD L. STORY, a citizen of the United States, and a resident of Everett, in the county of Middlesex and State of Massachusetts, have 5 invented an Improvement in Boiler-Coverings, of which the following description, in connection with the accompanying drawing, is a specification, like letters on the drawing representing like parts.

This invention has for its object to provide a novel 10 covering for boilers which is so constructed that access may be had to the seams of a boiler for inspection purposes without removing the entire covering of the boiler.

It has heretofore been proposed to make the entire 15 covering of a boiler in removable sections to facilitate inspection of the boiler. But as a usual thing it is necessary to inspect only the seams or at most a small part of the boiler surface, and to make the entire covering of the boiler in sections, any one of which is removable, involves a good deal of expense.

According to my invention I cover all parts of the boiler with the exception of the places where it is desired to inspect the same with a stationary permanent covering such as is usually employed around boilers; 25 and I make the portion of the covering which covers the parts of the boiler that it is desired to inspect removable so that access to these parts of the boiler can be readily secured. I have also provided a novel construction for the removable sections of the covering, 30 all as will be more fully hereinafter described and then pointed out in the appended claims.

In the drawings I have shown my invention as applied both to a horizontal boiler, and to what is commonly known as the "Manning" boiler.

35 Figure 1 is a plan view of a horizontal boiler having my invention applied thereto; Fig. 2 is a section on the line $x-x$, Fig. 1; Fig. 3 is a section on the line $y-y$, Fig. 1; Fig. 4 is a vertical section through a "Manning" boiler having my improvements applied thereto; and Fig. 5 is a section on the line $a-a$ Fig. 4.

Referring to Fig. 1, 3 is an ordinary horizontal boiler supported on the usual brick setting 4. This boiler is shown as having butt seams, but so far as my invention is concerned the boiler might have either lap or butt 45 seams. In constructing a horizontal boiler it is common to make it of several sections 5, 6 and 7, for instance, of sheet metal, which are connected together by girth-seams 8. The edges of each section are connected at 9 by either butt or lap seams; and the seams 50 9 of adjacent sections are usually arranged out of line with each other, as best seen in Fig. 1. In the butt seams shown in the drawings 10 and 11 are the two welt stripes which overlie the meeting edges 12 of the shell of the boiler. In inspecting a boiler of this 55 type it is the seams between the edges 12 of each section of the boiler that need inspection most, and ac-

cordingly I propose to cover the rest of the boiler with a permanent covering 13 of any suitable material, and to provide removable sections 14 over the seams which it is desired to inspect. As herein shown these removable sections 14 are made with a backing member 15 on which rests a body 17 of fire-felt, asbestos, or some other non-heat-conducting material, and this body is provided with a surface of cement. I prefer first to put a layer 18 of magnesia cement directly on the body 17, and then to use a surface layer 19 of Portland cement or some other cement which will make a hard waterproof surface for the section. The edges of the backing 15 are bent upwardly, as at 20, and preferably bent inwardly slightly, as at 20.

In making the section the body 17 of fire-felt, which usually comes in blocks, is placed on the backing 15, the sides 16 of the backing having previously been bent up as herein shown, and then a layer 18 of magnesia cement is poured on top of the body 17, and when it is sufficiently dry the surface layer 19 of Portland cement is applied. As the cement is applied it runs around the inwardly-bent edges 20 of the backing so that when the cement hardens the backing and fire-felt are all tied together. This construction has the 80 advantage that the removable section of the cover may be made in place. That is, the boiler, with the exception of the space directly over the seams, may be covered with the permanent covering 13, and then the backing member 15 may be cut to the proper shape 85 to fit the various openings left over the seams, and the removable sections 14 formed directly in the openings. In this way it is possible to readily make removable sections for any type of boiler and to make the 90 sections of any desired shape.

In Figs. 4 and 5 I have shown my invention applied to what is known as the "Manning" boiler. The Manning boiler is an upright boiler having the skirt 25 surrounding the fire-box 26 and forming one wall of the usual water leg 27, and the waist portion 28 of 95 smaller diameter than the skirt and forming the shell of the boiler through which the usual flues 29 pass. The skirt and the waist are connected by the ogee ring 30, and this ogee ring is relied upon to take up expansion and contraction. This is the part of the Manning boiler which is most apt to crack and which needs inspection, and in accordance with my invention I make the covering which surrounds the ogee ring 30 removable, while the covering 31 and 32 which surrounds the skirt and waist of the boiler is permanently attached. The covering 32 around the waist of the boiler may be supported on an angle iron support 33 or in any suitable way. The portion of the covering which surrounds the ogee ring 30 is made in sections 100 there being four or more of such sections as desired. 110 Each section has the backing 34 of wire mesh, the body 35 of asbestos, fire-felt, or some similar material and

the surface of cement, said surface preferably being made of two layers an inner one 36 of magnesia cement and an outer layer 37 of Portland cement. The edges 38 of the wire mesh are bent upwardly and embedded 5 in the cement as in the other embodiment of my invention.

Having fully described my invention, what I claim as new and desire to secure by Letters Patent is:—

10. 1. A boiler covering having a removable section presenting a backing of wire mesh, a body portion of non-heat-conducting material applied to one side only of said backing, and a surface coating of hard non-metallic waterproof material the edges of said backing embracing the body portion and being interlocked with said waterproof material.
15. 2. The combination with a boiler, of a covering permanently secured to all parts thereof except those which it is desired to inspect, and covering sections removably secured to said portions to which access is desired, said covering sections each presenting a backing of wire mesh, a body portion of non-heat-conducting material applied to one side only of said backing, and a surface coating of cement, the backing being bent outwardly at the sides 20 of the section to embrace the body portion, and the edges

of the backing being embedded in the cement whereby 25 said backing permanently holds the body portion and cement together.

3. The combination with a boiler, of a covering therefor having a removable section, said section comprising a backing of wire mesh, a body of non-heat conducting material applied to one side only of the backing, and a coating of Portland cement, the edges of said backing being embedded in the cement whereby said backing ties the cement coating and body together.

4. In a boiler covering, a removable section having a 35 body portion of fire-felt, a layer of magnesia cement, and an outer layer or surface coating of Portland cement.

5. A boiler covering provided with a removable section having a backing of wire mesh, a body portion of fire-felt, a layer of magnesia cement covering the fire-felt, and an 40 outer layer of Portland cement, the edges of the wire fabric being embedded in the cement.

In testimony whereof, I have signed my name to this specification, in the presence of two subscribing witnesses.

EDWARD L. STORY.
